(57) CLAIM

(*) Notice: This patent is subject to a terminal disclaimer.

The ornamental design for a combination rack for chemical analyzers, as shown and described.

(**) Term: 14 Years

DESCRIPTION

(21) Appl. No.: 29/110,772

FIG. 1 is a perspective view of the combination rack for chemical analyzers from the front left corner of the invention.

(22) Filed: Sep. 13, 1999

FIG. 2 is the front elevation thereof.

(51) LOC (7) Cl. 10-04

FIG. 3 is the rear elevation thereof.

(52) U.S. Cl. D10/80

FIG. 4 is the right side elevation thereof.

(58) Field of Search D10/80, 81; D8/319,

FIG. 5 is the left side elevation thereof.

D8/320; 16/110.5; 324/158 P, 158 F; 436/46,

FIG. 6 is the top plan view thereof; and,

50, 58

FIG. 7 is the bottom plan view thereof.
